UNITED STATES PATENT OFFICE.

RAYBURN F. KENNEDY, OF COLLEGE CORNER, OHIO.

TALLYING DEVICE.

1,211,170.

Specification of Letters Patent.

Patented Jan. 2, 1917.

Application filed February 23, 1916. Serial No. 79,967.

To all whom it may concern.

Be it known that I, RAYBURN F. KENNEDY, a citizen of the United States, residing at College Corner, in the county of Butler and State of Ohio, have invented certain new and useful Improvements in Tallying Devices, of which the following is a specification.

The present invention relates to game record boards and more particularly to new and useful improvements in indicating tally boards.

An object of my invention is to provide a tally board for games of various kinds for registering the number of points which each player has made as well as the number of games won by each player, obviating the necessity of keeping a record on a sheet of paper, which method is not only annoying but inefficient.

Another object of my invention is to provide a tally board for games in which a plurality of keys are provided depressible to indicate a "point" and having automatic means for retaining the keys in depressed position, and means for releasing simultaneously all of the keys when a game is finished.

Another object of my invention is to provide a tally board of the class described which is simple in construction, strong and durable, cheap to manufacture, and effective in operation.

Other objects and advantages to be derived from my invention will appear from the following detail description and the claims, taken with an inspection of the accompanying drawing in which,

Figure 1 is a top plan view of a tally board embodying the improvements of my invention, a portion of the same being broken away to illustrate in plan view the working parts, Fig. 2 is a transverse sectional view taken on the line 2—2 of Fig. 1 looking in the direction of the arrows, Fig. 3 is a longitudinal sectional view taken on the line 3—3 of Fig. 1, and Fig. 4 is an enlarged detail perspective view of a portion of the key releasing shaft.

Referring more particularly to the drawing wherein similar characters of reference designate like and corresponding parts throughout the various views, 1 designates in its entirety a casing having a base 2, end walls 3 and side walls 3'. A cover 4 is removably mounted on said casing and is

provided with suitable openings to accommodate the keys hereinafter described. It will be noted that the casing 1 is rectangular in configuration, but it is to be understood that I do not limit myself to this particular shape of casing.

My invention embodies point registering and indicating means, locking means therefor, and means for automatically releasing said registering means. The point indicating means comprises preferably a plurality of sets of depressible keys arranged in groups of five, these groups being practically identical in construction and therefore a description of one of the groups will suffice.

Referring to the groups of keys shown at the broken away portion of Fig. 1 and shown to advantage in Fig. 2 I have provided a plurality of shells preferably cylindrical and designated 5, said shells carrying keys 6, 7, 8, 9 and 10. The keys are maintained in the position best shown in Fig. 2 by means of coil springs 11 disposed between the lower extremities of the keys and the bottom of the shells 5. In order to maintain the key in indicating or depressed position, I provide locking means comprising preferably spring strips 12 arranged in parallelism and slightly spaced apart on a transversely extending beam or support 13 by means of fastening screws 14. The free extremities of the spring strips 12 are bent upwardly at right angles as indicated at 15 and 16 and laterally and outwardly bent as at 17 and 18 to provide locking tongues for a purpose which will hereinafter appear.

The body portion of the strip 12 on either side of the support 13 is slightly inclined upwardly as best shown in Fig. 2. A plurality of arms 19 and 20 are carried by the keys of each set, each of said arms being offset as at 21 and 22 in order to bring the free extremities thereof in uniform spaced relation adjacent the extremities of the spring strips 12. Suitable slots 23 are provided in the shells 5 to accommodate the arms 19 and 20. It will be seen that when the keys are depressed the arms 19 and 20 will be engaged under their respective locking springs, the laterally bent portions of said spring strips engaging under the upper marginal edges of the arms thereby retaining the keys in depressed position.

In order to automatically release all of a certain number of the sets simultaneously

I provide a pair of shafts 23 and 24 arranged in parallelism on each side of the support 13 and adjacent and above the free extremities of the spring strips 12. The 5 shafts 23 and 24 are provided with a plurality of parallel radially extending arms 25 and 26 arranged in spaced relation and adapted to be interposed between the free extremities of the arms 19 and 20. Normally 10 the arms 25 and 26 are in the position best shown in Fig. 2 the free ends being located slightly above the free extremities of the locking strips 12. Actuating levers 15 27 and 28 are carried by the free extremities of the shafts 23 and 24, respectively, said levers preferably being disposed at the right of a player. It will be seen that when the keys are in locked position and the lever controlling the particular set to which 20 said keys belong is depressed the arms carried by the key releasing shaft 23 or 24, as the case may be, engage the laterally bent portions of the spring locking strip 12 moving the same out of engagement with 25 the key arms allowing the same to be returned to non-indicating position by means of the springs 11.

As shown to advantage in Figs. 1 to 3 I provide further indicating means which 30 are identical in construction and a description of one will therefore suffice. In this instance I provide a shaft 29 mounted in a bearing bracket 30 and one wall of the casing 1, said shaft having a worm 31 on 35 the free extremity thereof engageable with a worm gear 32 carried on a vertical shaft 33 mounted in a bracket 34. An arrow or hand 35 is carried by the upper end of the shaft 33 and is arranged above the 40 top 4. A knurled manipulating handle 36 is mounted on the free end of the shaft 29 for imparting movement to the same.

I have provided means for indicating the 45 number of games won by a particular player designated 37, there being an indicator for each player using the device.

It will be seen that in operation an accurate account of a game or plurality of games may be kept by the players themselves 50 without the necessity of resorting to pencil and paper. It will be seen that after the tally has been counted up when a given game has been decided all of the keys may automatically be reset for another 55 game.

From the above description taken in connection with the accompanying drawing, it

is thought that a clear and comprehensive understanding of the construction, operation and advantages of my invention may 60 be had, and while I have shown and described by invention as embodying a specific structure, I desire that it be understood that I may make such changes on said structure as do not depart from the 65 spirit and scope of the invention as claimed.

What I claim as new and desire to secure by Letters-Patent is:—

1. A game tallying device of the class described, comprising a casing, having a plurality of depressible key members therein, a support, spring locking means comprising strips carried by said support and engageable with said key arms, said keys being independently depressible, and means 75 for simultaneously disengaging said spring locking means from said key arms to permit return of said keys to normal position.

2. A game tallying device of the class described, including a casing having a plurality of keys therein depressible against the tension of a spring, arms carried by said keys, spring locking means for said arms, and a shaft having a plurality of arms carried thereby for engagement with said locking means to release said keys and allow the same to return to normal position.

3. In a device of the class described, a casing, a support in said casing, a plurality of depressible key members in said casing, 90 arms carried by said key members and arranged in parallelism, spring locking strips carried by said support and having upturned laterally bent ends for engagement with the free ends of said arms, and a shaft having radially extending parallel spaced arms thereon for engagement with said spring locking members to disengage the same from said key arms and simultaneously release all of the keys.

4. In a game tallying device, a casing, a plurality of depressible key members in said casing, arms carried by said key members, a support, a plurality of locking strips carried by said support and having upturned 105 ends formed with laterally bent portions for engagement with the key arms, and means engageable with said upturned ends to move the laterally bent portions out of engagement with said arms to permit return 110 of said keys to normal position.

In testimony whereof I affix my signature.

RAYBURN F. KENNEDY.
